UNITED STATES PATENT OFFICE.

RUSSELL C. OLMSTED, OF HUDSON HEIGHTS, NEW JERSEY.

REENFORCEMENT FOR CONCRETE STRUCTURES.

Application filed November 23, 1926. Serial No. 150,195.

The present invention relates to new and useful improvements in reenforcing mats for concrete structures, and while the invention herein illustrated is shown and described as used in the construction of concrete roadways, it is to be understood that it is capable of use in other connections as well, such as a reenforcement for concrete walls, curbings, foundations or any type of concrete construction which employs intersecting elements in the reenforcing structure thereof.

One of the most effective forms of reenforcing structure for concrete roadways consists of two series of intersecting elements, preferably, although not necessarily in the form of bars. The two series of intersecting reenforcing elements are spaced with respect to each other, thus forming a lower series and an upper series of intersecting elements when the reenforcing structure is in position in the roadway.

In the operative position of this type of reenforcing structure, the upper and lower series of intersecting reenforcing elements are retained in spaced relation to each other by means of spacing elements or members, these spacing elements or members being preferably attached to the lower and upper series of intersecting reenforcing elements at certain or all of their points of intersection, and generally forming together with other suitable devices, means for securing the intersecting reenforcing elements together to form a reenforcing structure commonly known as a mat.

In other types of roadway construction, a single series of intersecting reenforcing elements is employed and said single series of reenforcing elements is supported in spaced relation with respect to the sub-grade of the roadway construction by specially constructed devices known as chairs which rest upon the sub-grade, the series of reenforcing elements being supported thereby, preferably at their points of intersection.

It is one of the objects of the present invention to provide a new and improved type of spacing element capable of use both to secure a lower and upper series of intersecting reenforcing elements, together in the form of a reenforcing mat, and as a so-called chair for supporting a single series of intersecting reenforcing elements in spaced relation to the sub-grade in the building of a concrete roadway when this type of reinforcement is employed.

Spacing elements of the general type mentioned have been heretofore employed, but so far as I am aware, they have been attached to the several intersecting elements of the reenforcing mat by a specially constructed device known as a "bar-t'y", and are not capable of securement in position by ordinary means, such, for example, as tying by wire, and it is a further object of the invention to provide a new and improved spacing element which, in addition to being capable of use with these specially constructed "bar-tys", readily lends itself to securement to the intersecting reenforcing elements by tying with ordinary tying wire, thus eliminating, where desired, the use of specially constructed devices such as "bar-tys".

In some instances, in roadway construction, where reenforcing mats formed of two series of intersecting reenforcing elements are employed, the parallelly extending reenforcing elements in one series together with their parallelly extending reenforcing elements in the other series are positioned exteriorly of the reenforcing mat, with the intersecting reenforcing elements in each series being positioned interiorly of the reenforcing mat. In another type of reenforcing mat, certain reenforcing elements of one series are positioned exteriorly of the reenforcing mat with their parallelly extending reenforcing elements in the opposite series positioned interiorly of the mat, and vice versa.

So far as I am aware, no spacing element has been devised with which both these types of reenforcing mats may be formed, and it is a further object of my invention to provide a spacing element, the use of which will permit of the formation and construction of reenforcing mats of either of the afore-mentioned types.

It is a still further object of my invention to provide a spacing element which may be more cheaply manufactured than spacing elements now employed and with which I am familiar, thus reducing materially the cost of reenforcement mats or structures for concrete roadway construction.

With the above and other objects in view, which will appear as the nature of the invention is more clearly understood, reference is had to the accompanying drawings wherein is illustrated the preferred forms of my invention, and in which,

Figure 1 is a detail perspective view broken away to show a reenforcing mat in which the

spacing elements are constructed in accordance with the present invention;

Figure 2 is a detail sectional view taken on the line 2—2 of Figure 1;

Figure 3 is a detail sectional view taken on the line 3—3 of Figure 2;

Figure 4 is a detail plan view;

Figure 5 is a detail perspective view of a slightly modified form of spacing element; and

Figure 6 is a detail plan view showing the manner of attaching intersecting reenforcing elements and a spacing element together by means of ordinary tying wire.

As will be noted by reference to the accompanying drawings, a spacing element constructed in accordance with the present invention is preferably formed from a relatively narrow strip of material and comprises a body portion 10, upon each end of which a loop is formed, these loops being designated by the reference numeral 12.

The loops 12, are preferably formed by bending the ends of the body portion 10, as at 14, to provide right angularly disposed extensions 16 which, in turn, are bent as at 18 to provide right angular end portions 20. While in the present illustration of the invention, the loops 12 are shown as of right angular formation, it may, in some instances be desirable to form them in other shapes, and I do not wish to be limited to the form of loops shown, but wish it understood that loops of any formation fall within the scope of my invention.

The wall of each of the loops formed by the extension 16 is cut out as at 22, and the cut-out portion also preferably extends a short distance into the body portion 10 and the end portions 20, as designated at 24 and 26, respectively.

As heretofore stated, one of the most effective forms of reenforcing mat or structure for concrete roadways consists of an upper and lower series of intersecting elements arranged in spaced relation to each other, and a spacing element constructed in accordance with the present invention particularly lends itself to reenforcing mats or structures of this character.

Such a roadway construction is shown in Figure 1 of the accompanying drawings in which the upper series of intersecting reenforcing elements is designated by the reference character A, the lower series of intersecting elements being designated by the reference character B. In this illustration, the sub-grade is designated by the reference character C, the body of the roadway or "slab" as it is known in the art, being designated by the reference character D.

As will be noted by reference to the drawings, the lower series of intersecting elements are shown in the form of steel bars 30 and 31, the upper series being preferably of a simi-

lar nature, and designated by the reference numerals 40 and 41. While in the present instance these reenforcing elements are shown as steel bars, it is to be understood that the invention is not limited to use with this type of reenforcing element alone, but may by slight modification be readily adapted to use with all types of reenforcing elements.

In constructing this type of reenforcing mat or structure, it will be noted that the several spacing elements are arranged entirely within the confines of the mat, and are supported upon the lower or outer reenforcing elements 31 of the lower series B. This outer or lower reenforcing element is received in the cut-out portion 22 of the lower bar receiving loop of each of the spacing elements with which it engages, the side walls of the cut-out portions serving to position the reenforcing element 31 and aid, with other means to be hereinafter referred to, to retain said reenforcing element against accidental displacement.

The inner reenforcing element 30 of the lower series is received in the lower loop of each of the spacing elements which it engages, and intersects the several spacing elements 31 at this point. After the intersecting elements have been thus arranged, a bar-ty 35 of any suitable type is engaged with reenforcing elements 30 and 31 to securely hold them with respect to each other and lower end of the spacing elements.

In the assembly thus far carried out, it will be noted that the spacing elements occupy a vertical position and are supported upon the outer or lower reenforcing element of the lower series B.

The outer or upper reenforcing element 40 of the upper series A, it will be noted, occupies a position in the cut-out portion 22 of the upper reenforcing element receiving loop of the spacing elements, said reenforcing element 40 resting thereon and being supported thereby. The inner or lower reenforcing element 41 of the upper series A is received in the upper reenforcing element receiving loop and is adapted to be suspended from the reenforcing element 40 in the finished reenforcing mat. Any suitable means may be employed for suspending the reenforcing elements 41 from the reenforcing elements 40 and I therefore do not wish to be limited to the means shown in the accompanying drawings which constitutes a conventional type of bar-ty such as 42.

It will be noted that in the form of reenforcing mat thus far described, each upper or outer reenforcing element of the upper series A of the reenforcing elements is parallel with its respective lower or outer reenforcing element of the lower series B of reenforcing elements, and that the inner reenforcing elements of each series also occupy positions in parallelism. In some instances,

however, it is desirable to form a reenforcing mat wherein the outer or upper reenforcing elements of the upper series A occupy positions in parallelism with their respective inner reenforcing element of the lower series B of reenforcing elements with the inner reenforcing element of the upper series A parallel with its respective outer reenforcing element in the lower series B.

5 In Figure 5 of the drawings, I have illustrated a spacing element which readily adapts itself to the formation of a reenforcing mat of this last mentioned type, and which comprises a body portion 50 having reenforcing element receiving loops 51 at its opposite ends, said loops being cut out to provide reenforcing element receiving openings 52. In order to form a reenforcing mat of the last above mentioned type, however, it is necessary that the reenforcing element receiving loops 51 be positioned angularly with respect to each other, and to obtain this angular relative position of the reenforcing element receiving loops, the body portion of 20 the spacing element is twisted on its longitudinal axis as designated at 55, the desired angular position of the reenforcing element receiving loops being determined by the amount of twist given to the body portion of 25 the spacing element.

In Figure 6 of the drawings, I have shown the intersecting reenforcing elements secured together and to the spacing element by means of ordinary tying wire in lieu of bar-tys, said 30 tying wire being designated by the reference numeral 54. This tying wire is passed around the intersecting reenforcing elements and the loop of the spacing element with which they are associated preferably in the 35 form of a plurality of loops 55, and this manner of forming a unitary structure has been found by me to be very effective and somewhat cheaper than where bar-tys are employed.

40 When the spacing element is employed as a chair, that is to support a single series of intersecting reenforcing elements in spaced relation to the sub-grade of the roadway being formed, the lower reenforcing element receiving loop serves as a foot upon which the spacing element rests upon the sub-grade, the reenforcing elements being secured to the upper end of the spacing elements as heretofore described.

45 While I have illustrated the invention in what may be termed its preferred forms, I wish it understood that it may be executed in various other forms not herein illustrated but clearly within its scope, and I, therefore, 50 wish it understood that all forms which fall within the purview of the appended claims are covered herein.

55 What is claimed as new is:

1. A spacer element for concrete reenforcing elements, said spacer element comprising

a relatively narrow strip of material constituting a body portion, reenforcing element receiving loops formed on the ends of said body portion, and an outwardly disposed reenforcing element receiving opening formed 70 in each of said loops, and adapted to receive an outer reenforcing element therein at an angle to a reenforcing element carried in the reenforcing element receiving loop.

2. A reenforcing mat for concrete structures comprising two series of reenforcing elements, the reenforcing elements in each series being arranged in intersecting relation, and means for securing said two series of intersecting reenforcing elements, together in 75 spaced relation, said means comprising a plurality of spacing elements, each comprising a body portion, a notched loop formed at each end of the body portion, each of said loops being adapted to receive an inner reenforcing element and the notch of each loop being adapted to receive an outer intersecting reenforcing element, and means for securing the intersecting reenforcing elements and the 80 spacers together to provide a unitary structure.

3. A reenforcing mat for concrete road structures comprising a lower series of reenforcing elements arranged in intersecting relation, an upper series of reenforcing elements arranged in intersecting relation, each of said series including an inner and outer reenforcing element and means for securing said series of intersecting reenforcing elements together in spaced relation, said means 95 comprising a spacer having end loops for the reception of the inner reenforcing elements in its respective series, and formed with a notch for the reception of the outer intersecting reenforcing element in its respective 100 series, and means for securing said intersecting reenforcing elements and said spacer together to provide a unitary structure.

4. A spacer element for concrete reenforcements, said spacer element comprising a body 110 member and a reenforcing element receiving loop at each end of said body member, an inner reenforcing element positioned within each of said loops, said loops each having an outwardly disposed cut-out portion for the 115 reception of a reenforcing element arranged in intersecting relation with the reenforcing elements positioned within the loops.

5. A reenforcing mat for concrete structures, said mat comprising a lower series of 120 intersecting reenforcing elements, a plurality of spacer elements secured to the lower series of reenforcing elements at the points of intersection of the reenforcing elements thereof, an upper series of intersecting reenforcing elements, the outer reenforcing elements of the upper series of reenforcing elements resting upon the upper ends of their respective spacer elements, and means for securing said outer reenforcing elements of the upper series 125 130

of reenforcing elements to their respective spacer elements, said securing means serving to suspend the inner reenforcing elements from the outer reenforcing element of said 5 upper series of said reenforcing element.

6. A concrete reenforcing structure comprising a spacer element, a reenforcing element receiving loop provided at one end thereof, an outwardly disposed notch formed 10 in said loop, an outer reenforcing element mounted in said notch, an inner reenforcing element positioned in said loop, and means for securing said outer reenforcing element in said notch, and suspending the inner re- 15 enforcing element from said outer reenforcing element.

7. A concrete reenforcing structure comprising a spacer element, a reenforcing element receiving loop provided at one end thereof, an outwardly disposed notch formed 20 in said loop, an outer reenforcing element

mounted in said notch, an inner reenforcing element positioned in said loop, and means for securing the outer reenforcing element in said notch and securing the inner reenforc- 25 ing element in said loop.

8. A concrete reenforcing structure comprising an upper series of intersecting reenforcing elements, a lower series of intersecting reenforcing elements, and a plurality of spacing elements for maintaining said upper and lower series of reenforcing elements in spaced relation, said spacing elements each comprising an elongated body portion having at each end a loop for the reception of the inner re- 30 enforcing element of its respective series, and an outwardly disposed notch providing a seat for the outer reenforcing element of its 35 respective series.

Signed at New York city, N. Y., this 22nd 40 day of November, 1926.

RUSSELL C. OLMSTED.
